ABSTRACT: A mechanical pneumatic time delay device has an actuating arm attached to a piston located within a housing. A spring and a bellows for sealing the housing surrounds the actuating arm. A chamber within the housing adjacent the piston is filled with CO₂ under pressure to compress the spring. A porous restrictor is positioned in a passageway in one wall of the housing. Support discs are provided on both sides of the restrictor. A puncture diaphragm is positioned adjacent the restrictor on the side remote from the pressure chamber. Puncture of the diaphragm initiates the time cycle.

1
MECHANICAL PNEUMATIC DELAY TIMER

BACKGROUND OF THE INVENTION

Time delay device of various types are known in the art for providing a time delay between the occurrence of two events. Such time delay devices may be electrical, chemical or mechanical. Some of the mechanical timers depend on the flow of a gas through a gas permeable membrane or container.

In some self-destruct systems, rugged-dependable long time delay timers are required. Pneumatic timers are known to be accurate for short time delays, but their accuracy is known to decrease when long time delays are required.

According to this invention a mechanical pneumatic time delay device is provided which is rugged in construction and which will operate within approximately ± 10.5 percent of the expected or designed time delay. A pressure chamber and a porous restrictor are provided wherein the initial pressure in the chamber and thickness of the restrictor determines delay time.

BRIEF DESCRIPTION OF THE DRAWINGS

FIG. 1 is a sectional view of a mechanical pneumatic timer according to the invention;

FIG. 2 is a sectional view partially in block form showing the mechanical pneumatic timer in operating position before puncture of the diaphragm;

FIG. 3 is a sectional view partially in block form showing the mechanical pneumatic timer in operating position after puncture of the diaphragm; and

FIG. 4 shows delay time vs. restrictor thickness for a plurality of tests.

DESCRIPTION OF THE PREFERRED EMBODIMENT

Reference is now made to FIG. 1 of the drawing which shows a pneumatic time delay device 10 having a housing 11 with a hollow cavity 12 therein. The cavity 12 has a portion 14 of smaller cross section than portion 16. The portions 14 and 16 may have a circular cross section, a rectangular cross section or other cross section. A passageway 18 having an enlarged portion 20 extends from hollow cavity 12 to the outside of the housing 10. A restrictor 22 is positioned in the enlarged portion 20 of passageway 18. A pair of restrictor supports 23 and 24, made for example of sintered copper, stainless steel or bronze, are positioned on either side of the restrictor 22. The restrictor may be made of a silicone rubber restrictor material, for example such as made by Dow Corning Corporation under the trade names "Silastic 50" or "Silastic 152".

"Silastic 50" has been found to be more permeable to CO_2 than "Silastic 152". With a CO_2 gas pressure of 500 p.s.i.g. and a restrictor with a thickness of .025 inch, the flow rate was found to be 0.444 cc./min./in.² for "Silastic 152" and with the same pressure and thickness, the flow rate for "Silastic 50" was found to be 6.73 cc./min./in.². For any particular restrictor material the flow rate is a function of the thickness of the restrictor material and the pressure of the gas. Therefore, the pressure of the CO_2 in chamber 35 and the thickness of the restrictor may be selected to give the desired delay time for the particular restrictor material used.

A member 26, of a material such as aluminum, has a recess 28 machined therein to provide a thin puncture diaphragm 29. The diaphragm is scored in the usual manner to provide rapid breaking when hit by a puncture point 30 driven by a puncture

mechanism 31. The restrictor support backup plug 32, positioned in recess 28, has a passage 33 therein. A thin spacer 34 between plug 32 and diaphragm 29 may be provided when needed.

5 A piston 36 having a plunger 37 is positioned within cavity portion 12 and forms a pressure chamber 35. Plunger 37 has a projection 38 which extends through an opening in end cap 39 to operate a utilization device 50 as shown in FIGS. 2 and 3. A spring 40 acts to urge the piston 36 toward chamber 35 to 10 retract the plunger 37. A bellows 42 is sealed to piston 36 and end plate 39 to seal cavity 12 so that gas does not leak out around plunger 37. A fill tube 45 is provided adjacent chamber 35.

In the operation of the device, the chamber 35 is filled with 15 a gas such as CO_2 to the pressure desired which for one device tested was 400 p.s.i. The device was allowed to soak for 1 hour after which the tube 45 was sealed off. The projection 38 then extends out of housing 10 to move operating rod 48 of a utilization device 50 to the position shown in FIG. 2. When the 20 diaphragm 29 is punctured by means of a puncturing point 30 carried by a swinging or sliding member of a conventional design and operated by a mechanism 31, the gas leaks out through the restrictor 22 until the pressure in the chamber 14 drops to a pressure which permits the spring to move piston 36 25 to the left and retract projection 38 thus permitting the operating rod 48 to operate the utilization device 50, which may, for example, be a self-destruct mechanism or any other apparatus for which time delay operation is desired. The pressure at which spring 37 permits movement of the piston will be 30 determined by the particular design, which for the design built was approximately 25 p.s.i.

FIG. 4 shows the delay time vs. restrictor thickness for a test unit where the gas in chamber 35 was CO_2 at 400 p.s.i.g. Restrictor thicknesses from 0.0042 to 0.0099 inch were used 35 for this test. The porous metal support discs were 0.055 inch thick.

Delay times of 51.3 hours have been achieved with a 0.1 inch restrictor with the initial pressure of the CO_2 gas in chamber 35 at 400 p.s.i.g.

40 There is thus provided a dependable, rugged pneumatic delay timer for use where relatively long delay times are desired.

We claim:

1. A time delay device comprising: a housing member; a 45 cylindrical cavity within said housing member; a piston forming one wall of a pressure chamber within said cavity; a plunger member extending through the wall of said housing; said plunger member being operatively connected to said piston; spring means, surrounding said plunger and engaging said piston for urging said plunger inwardly of said housing member; a gas under pressure within said pressure chamber for compressing said spring and for moving the end of said plunger in a direction away from the pressure chamber; means, surrounding said plunger and attached to said piston 50 and said housing member for preventing the flow of gas around the plunger and out of said cavity; a gas passageway extending from said pressure chamber to the exterior of said housing; a frangible diaphragm sealing said passageway; means including a silicon rubber restrictor positioned in the 55 passageway to restrict the flow of gas from said pressure chamber after said frangible diaphragm has been punctured; and a support means positioned on each side of the restrictor means.
